NARROW FABRIC

Bertram J. Goldsmith, Neshanic, N. J.

Application May 24, 1938, Serial No. 209,718

4 Claims. (Cl. 139—384)

This invention relates to narrow fabrics such as edging strips, ribbons or tapes, and is intended primarily for use as edge bindings and trimmings for blankets and similar articles, although said narrow fabrics are not limited to such uses. The invention is also concerned with blankets and similar articles provided with such edging or binding strips.

One object of the invention is to provide an edge binding or trimming strip which may be attached to the blanket or other article by concealed lines of stitching.

Another object of the invention is to provide a blanket or similar article with a binding or trimming strip of narrow fabric which, in addition to its function as a binding strip, also improves the appearance of the blanket and adds to the length or width thereof, or both to the length and width thereof, when the strip is attached to the ends or to the sides, or both to the end and side edges of the blanket, as the case may be.

It is also an object of the invention generally to provide improved edge bindings or edging strips whereby to improve the appearance of the blankets or other articles to which such edging or binding strips are attached.

The above objects of the invention and other objects which might hereinafter appear will be fully understood from the following description considered in connection with the accompanying drawing.

In the drawing:

Fig. 1 is a perspective view of a blanket provided with edging strips of the present invention;

Fig. 2 is a sectional view on the line 2—2 of Fig. 1;

Fig. 2a is a view similar to Fig. 2 showing a modification;

Fig. 3 is a fragmentary perspective view of one of the edging or binding strips embodying the present invention;

Fig. 4 is a view similar to Fig. 1 showing another form of the invention;

Fig. 5 is a sectional view on the line 5—5 of Fig. 4;

Fig. 6 is a plan view of a blanket showing binding strips attached to the four edges thereof;

Fig. 7 is a fragmentary perspective view of a woven fabric from which bindings may be made in accordance with another form of the invention.

Referring now to the drawing in detail, the blanket indicated generally by the reference numeral 10, may be made of any suitable blanket

material. As here shown, said blanket is provided at the head and foot ends thereof with edging strips 12 of the present invention, said strips being folded over the marginal edge portions of said ends of the blanket. The binding material 12 may be of any suitable width whereby to permit the same to be folded over the edge portions of the blanket at both sides thereof. Said binding material is in the form of woven strips of any suitable fabric, such as silk, rayon 10 or other material and, as clearly shown in Figs. 2 and 3 of the drawing, has divided or splayed side edge portions 14 which extend preferably for the full length of said binding strips. Splayed portions 14 are preferably formed integral with the main or body portion 16 of the binding strip in the weaving of the latter. As clearly shown in the drawing body portion 16 is substantially wider than marginal edge portions 14.

As here shown, one of the parts 18 of each splayed portion 14 is somewhat wider than its companion part 20 so that when the binding strip is folded over the edge portions of the blanket and stitched in position, parts 18 extend somewhat beyond the edges of parts 20 for covering 25 the latter and it will be understood that when the binding strips are attached to the blanket the strips are folded so that the wider parts 18 of the splayed portions are disposed outermost and overlie parts 20 at both sides of the blanket. 30 The outer edges of parts 18 and 20 are selvedge edges. Said strips are each secured in position by one or more lines of stitching, here shown as one line of stitching 22, which passes through both parts 20 of each strip and through the blanket but does not pass through outermost parts 18 of the splayed portions of said strips. Stitching 22 is therefore concealed from view whereby the blanket has a neater and more attractive appearance than is the case with blankets in which conventional binding strips are attached to the blanket by lines of stitching which pass through the binding strips and are exposed to view on the outer surfaces of said strips. As illustrated in Fig. 6 the side edges of the blanket may also be provided with bindings 12 of the present invention. It will be understood that the binding strip may have only one divided marginal edge portion instead of two. Thus, as illustrated in Fig. 2a, strip 12a, which in other respects is the same as strip 12, has as here shown only one splayed edge portion 14a constituted by divided parts 18a and 20a. In this case, the stitching passes only through part 20a, through the blanket and through the other edge portion of the strip, 55

the latter being on the inner side of the blanket. The edge of the strip 12a opposite splayed portion 14a is preferably a selvedge edge.

As hereinbefore stated, it is also an object of the present invention to provide binding or edging strips which in addition to their normal functions of binding the edges of the blanket, also add to the width or length thereof whereby less blanket material may be used for a blanket of the same overall size. Pursuant to this object of the invention, there is provided, as illustrated in Figs. 4 and 5 of the drawing, binding or edging strips 24 which are secured to the edges of the blanket 26 and which project outwardly therefrom in such manner as to add to the length of the blanket. It will be understood that similar strips may be attached to the side edges of the blanket for increasing the overall width of the blanket or for reducing the width of the blanket material 26 for the same overall width of the blanket. Strip 24 is preferably woven of any suitable material and, as here shown, comprises an outer body portion 28 and an integral inner divided or splayed portion 30 constituted by separable parts 32 woven integral with part 28. As clearly shown in Fig. 5, body portion 28 is substantially wider than marginal edge portion 30. Said binding 24 is finished as a double-face binding, and parts 32 may be of any suitable thickness. For example, the combined thickness of parts 32 may be the same as the thickness of the part 28 or may have a thickness which is greater or less than the thickness of part 28. Divided portion 30 is secured to the marginal edge portion of the blank proper by one or more lines of stitching, here shown as one line of stitching 34. Strips 24 may vary in width, although ordinarily the preferred width is from one inch to two and a half inches. Parts 28 and 32 preferably have selvedge edges.

In accordance with another form of the present invention, the binding strips, instead of being woven initially in narrow fabric form, may be woven in a relatively wide fabric and subsequently reduced to the binding or narrow fabric widths. Thus as illustrated in Fig. 7, there is provided a relatively wide fabric 40 having spaced intermediate widths 42 and end widths 44 woven integrally with tubular portions 46. Fabric 40 can be readily formed into bindings or edging strips similar to strips 12 and 24 by cutting said fabric along longitudinally extending lines medially of the tubular portions 46, the lines of cutting being indicated by the dotted lines 48. Fabric 40, like the narrow fabrics woven into the bindings 12, 12a and 24, may be made of any suitable materials, such as, for example, silk, artificial silk or rayon, cotton, etc. The ends 44 of fabric 40 may be woven with selvedge edges. It will be understood that the tubular portions

46 as well as the end portions 44 and 42 may vary in width, and further that in the same woven fabric said portions 42, 44, and 46 may be of different widths.

While I have shown and described the preferred embodiments of my invention, it will be understood that the invention may be embodied otherwise than as here shown. Accordingly, I do not wish to be limited precisely to the forms of the invention herein shown or described, or to any one of them, except as may be required by the scope of the appended claims.

Having thus described my invention, what I claim and desire to secure by Letters Patent is:

1. A narrow fabric of the class described comprising a length of fabric having a body portion and a longitudinally extending marginal edge portion comprising two superposed thicknesses united at their inner edges with the body portion and separate from each other at their outer portions, one of said thicknesses being wider than the other.

2. A narrow fabric of the class described comprising a length of fabric having a body portion and a longitudinally extending marginal edge portion comprising two superposed thicknesses woven integrally and united at their inner edges with the body portion and separate from each other at their outer portions, one of said thicknesses being wider than the other.

3. A blanket or similar article having attached to an edge portion thereof a fabric edging strip having a body portion provided with opposite divided marginal edge portions, each of said marginal edge portions comprising two superposed thicknesses woven integrally and united at their inner edges with said body portion and separate from each other at their outer portions, said body portion of the edging strip being folded over said edge portion of the blanket and the opposite divided marginal edge portions of said strip positioned at opposite sides of said blanket, and stitching for securing said strip to the blanket passing through the latter and through the inner thickness only of said marginal edge portions.

4. A blanket or similar article having attached to an edge portion thereof a fabric edging strip comprising a longitudinally extending body portion of single thickness and an integrally woven and united section of two thicknesses extending longitudinally of said body portion, said body portion being folded over the edge portion of said blanket at both sides of the latter with said section of two thicknesses disposed at one side of the blanket and a line of stitching passed through the inner thicknesses only of said section for securing the edging strip to the blanket, the outer thickness of said stitched marginal part overlying and concealing the said stitching.

BERTRAM J. GOLDSMITH. 60
